TRAFFIC SIGNAL

Earl F. Hubacker, Highland Park, Mich., assignor
to a partnership consisting of J. Stuart Bick-
nell, Mark H. Bicknell, Harold Hanchett, and
W. James Olson, Clare, Mich.

Application December 5, 1941, Serial No. 421,722

12 Claims. (Cl. 177—337)

This invention relates to electric traffic signals and particularly to a new and improved mechanism for controlling the operation thereof.

A principal object of the invention is to provide a new and improved form of electric traffic signal and controls therefor.

Another object of the invention is to provide an electric traffic signal which is adapted to utilize a battery as the source of current.

Another object of the invention is to provide a new, improved and more simplified circuit and control means therefor for an electric traffic signal.

Another object of the invention is to provide an electric traffic signal with a simplified and very inexpensive means of adjusting the timing of the lights in one direction relative to the timing of the lights in the other direction.

Another object of the invention is to provide a new and improved electric traffic signal control which is very simple in construction, very dependable in operation, and which is particularly adapted for use with a battery as a source of current.

Other objects and advantages of the invention will be apparent from a consideration of the following specification taken in conjunction with the accompanying drawings, of which there are two sheets, and wherein:

Fig. 1 is a diagrammatic illustration of an electric traffic control mechanism embodying the invention;

Fig. 2 is a plan view of a thermostatic switch useful in practising the invention;

Fig. 3 is a diagrammatic illustration of the electrical interlock between the sets of lights; and

Fig. 4 is a diagrammatic illustration of another embodiment of the invention.

Referring now to Fig. 1, there is diagrammatically illustrated an electric traffic control mechanism embodying the invention and which in general comprises a series of red lights marked RE, RS, RW, and RN, and which are adapted to face in four directions at a traffic intersection, the letter R indicating that the lamp or light is red and the second letter indicating that the light faces east, south, west, or north, whichever the case may be. A series of green lights marked GE, GS, GW, and GN also are provided, the letters indicating that the lamp is green and faces east, south, west, or north, as the case may be. A series of amber lights marked AE, AS, AW, and AN also are provided, the letter A indicating that the light is amber, and the second

letter indicating that the light faces east, south, west, or north, as the case may be.

The lights marked RS, RN, GE, and GW are all connected to the electrical conductor 10, and each of these lamps is grounded so that when the circuit is closed all of the lamps connected to the conductor 10 will be actuated or lit. The lamps marked RE, RW, GS, and GN are connected to the conductor 12 and are all grounded so that when the circuit, of which the conductor 12 forms a part, is closed, the lamps connected to the conductor 12 will be actuated or lit. Means as hereinafter described are provided for alternately lighting the lamps connected to the circuits 10 and 12.

The lamps are adapted to be arranged or supported in a suitable housing which is adapted to be arranged at a traffic intersection for controlling the flow of traffic through the intersection, and, as in the case of a conventional traffic signal, when the green lights facing north and south and the red lights facing east and west, for example, are actuated, the north and south bound traffic is allowed to move while the east and west bound traffic is halted. When the lights change, the north and south red lights are actuated to halt the north and south traffic, while the east and west green lights are actuated to permit movement of the east and west traffic.

The conductors 10 and 12 are connected through the control mechanism hereinafter described to a source of current, such as a battery indicated at 14, through a manually controlled switch indicated at 16. The battery 14 is grounded, and when the switch 16 is closed the control mechanism hereinafter described is adapted to alternately operate the sets of lights as previously indicated. The lights, as well as the mechanism previously indicated, are arranged in a suitable housing, and when a battery is used it will be apparent that the housing may be of a portable nature, that is, the traffic control unit including its source of power will be self-contained and may be arranged for operation in temporary locations or in locations where a source of power is not available.

The control mechanism as illustrated in Fig. 1 comprises thermostatically controlled switches indicated generally at 18 and 20. An electric conductor 22 connected to one side of the battery 14 when the switch 16 is closed is connected to one end 24 of a resistance 25, the other end 28 of which is connected to the movable element 30 of a thermostatic switch 32 which is connected through a double switch 34, when the same is

closed, to the conductor 10. The switch 32 is normally closed, and the switch 34 is controlled by a magnetic relay, the coil 36 of which is grounded at one end and connected through the switch 32 and resistance 26 to the conductor 22 at the other end.

The movable arm 38 of the relay has connected to it the movable contacts of the switch 34, and when the switches 16 and 32 are closed, the coil 36 is energized and will hold the switch 34 closed, thereby completing the circuit from the battery 14 through switch 16, conductor 22, resistance 26, switch 32, switch 34, conductor 10, and the lamps connected thereto. A variable resistance 40 is arranged in parallel to the resistance 26 for the purpose hereinafter described.

Amber lights AE and AW are connected to conductor 42, which forms a part of the circuit for the amber lights, and which is connected to one of the stationary contacts of a double switch 44 which is closed by the relay when the coil 36 thereof is energized. The other stationary contact of the switch 44 is connected by conductor 46 to the end 23 of the resistance 26 through thermostatic switch 48 which, as illustrated in Fig. 1, is open.

As previously indicated and with the parts arranged as illustrated in Fig. 1, current is flowing in the circuit which controls the RS, RN, GE, and GW lights and also through the coil 36 of the magnetic relay. Resistance 26 forms a heating element or thermostatic means for actuating the movable contact 30 of switch 32 and also the movable element 50 of switch 48. While the switch 32 is closed, the heating element 26 is adapted to actuate the movable element 50 of the switch 48 and close the same, thereby turning on the amber lights AE and AW. After a predetermined time interval the heating element 26 is adapted to actuate movable element 30 of the switch 32 to open the same, which breaks the circuit through the magnetic relay thereby opening the switches 34 and 44 and breaking the circuits through the red, green and amber lights connected to the conductors 10 and 42.

A somewhat diagrammatic illustration of a thermostatic switch which may be employed is illustrated in Fig. 2, and may consist of a base 54 upon which the various elements are mounted. The conductor 22 may be connected to a binding post 56 to which the end 24 of the resistance 26 is connected, the other end 23 of the resistance being fastened to an arm 58 which is mounted on a spring leaf 60, which in turn is mounted upon the block 62. The movable element 30 of the switch 32 may comprise a spring leaf and be mounted upon stationary pivot 64 and movable pivot 66 formed on the member 58. The switches 32 and 48 are illustrated in Fig. 2 in the same position as in Fig. 1.

The movable element 50 of the switch 48 may comprise a spring leaf and be mounted between the movable pivot 66 and a stationary pivot 68 and, as illustrated, the contact carried by the movable element 50 of the switch 48 is positioned against a stop 70. The flow of current through the resistance 26 will cause the same to lengthen, thereby permitting the movable pivot 66 to move in a clockwise direction with regard to the block 62 under the bias of the spring 60. After the current has been flowing through the resistance 26 for a predetermined time interval, for example 25 seconds, the movable pivot 66 will move sufficiently to cause the movable element 50 of the switch 48 to engage the stationary contact

thereof. This will occur when the movable element 50 moves to the other side of the line formed by the stop 70 and the stationary pivot 68. When the switch 48 closes, the amber lights 5 will come on as previously described. After a further time interval, for example five seconds, the movable pivot 66 will have moved to the other side of a line formed by the stationary contact of the switch 32 and the stationary pivot 64 and will cause the movable element 30 of the switch 32 to move and open the switch 32, thereby breaking the circuit through the lamps connected to the conductors 10 and 42 and the circuit through the relay 36 as previously described.

15 The variable resistance 40 in parallel with the heater element or resistance 26 provides for shunting current around the resistance 26 and thereby controls the heating time thereof. As the resistance 40 is increased, the time required for the element 26 to heat up and actuate the switches 32 and 48 will be decreased, while as the resistance 40 is decreased the time element required for the resistance 26 to actuate the switches 32 and 48 will be increased. Thus, by adjustment of the resistance 40, the time interval that the lamps connected to the conductors 10 and 42 are energized may be varied, within certain limitations as hereinafter set forth.

16 The amber lights AS and AN are connected to a conductor 72 and are adapted to be energized with and at the end of the period of energization of the green lamps GN and GS. The control mechanism for the circuit through the lamps connected to the conductors 12 and 72 is the same as that for the lamps connected to the conductors 10 and 42, and to indicate the corresponding parts of the control means for the conductors 72 and 12, the same reference characters employed in connection with the control means for the conductors 10 and 42 are used with the prefix 1 added thereto. Thus the conductor 22 is connected to one end 124 of resistance 126, the other end 128 of which is connected to the movable element 130 of switch 132 which normally is closed. The switch 134 of the relay 136 and which controls the circuit through the lamps connected to the conductor 12 is open, as is the switch 144 which controls the circuit through the amber light connected to the conductor 12, when the switches 34 and 44 are closed. The switches 132, 148, variable resistance 140, relay 136, and other parts are identical in construction and operation to the corresponding parts of the control mechanism for the conductors 10 and 42, and hence need not be further described except with reference to the means which controls the alternate operations of the two circuits.

17 The movable contacts of the switches 34 and 44 are carried by the element 38, which may comprise a movable arm pivoted at 76 as illustrated in Fig. 3. When the circuit through the coil 36 is closed as shown in Fig. 1, the element 38 will be positioned as shown in full lines in Fig. 3, and when the circuit through the coil 36 is broken, the element 38 will move to the dotted line position indicated in Fig. 3. The movable element 132 of the relay 136 may be pivoted at 176 and have a lug 178 which projects into an opening 180 formed in the end of the arm 38 so that when the coil 36 is energized and the arm 38 positioned as shown in full lines in Fig. 3, the arm 138 will be held in the position shown in full lines in Fig. 3. In this position the movable contacts of the switches 134 and 144, which also

may be carried by arm 38, will be positioned as illustrated in Fig. 1.

When the circuit through the coil 36 is opened, the arm 38 will move to the dotted line position illustrated in Fig. 1 and, since the circuit through the coil of the relay 136 is already closed due to the fact that the switch 132 is closed, the arm 138 will move to the dotted line position shown in Fig. 3. Note that when the arm 138 is in the position shown in dotted lines in Fig. 3 that the arm 38 cannot return from its dotted line position to its full line position even if the coil 36 is energized, as the end of the arm 138 is in the path of movement of the arm 38. When the circuit through coil 36 is opened, arm 38 which carries the movable contacts of switches 34, 44, 134, and 144 will move and open switches 34 and 44 and close switches 134 and 144, and vice versa.

When the circuit through the coil 136 is broken, which happens when the heating element 126 is heated sufficiently to open the switch 132, the arm 138 will move from its dotted line position to its full line position in Fig. 3 and permit the arm 38 to return to its full line position, thereby closing the switches 34 and 44 simultaneously with the opening of the switches 134 and 144. Thus it will be apparent that when the switches 34 and 44 are open, the switches 134 and 144 will be closed so as to actuate the other set of lights, and when the switches 134 and 144 are open the switches 34 and 44 will be closed. The foregoing provides an interlock between the two circuits which locks one circuit open when the other is closed.

The variable resistance 140, similar to the variable resistance 40, may be set for varying the time interval that the switches 134 and 144 are closed.

When the switch 32 is opened, thereby also effecting the opening of the switches 34 and 44, the circuit through the resistance 26 is broken. As soon as the resistance 26 cools down, the switch 48 will open and the switch 32 will close, and the time that the switch 132 is closed after the switches 134 and 144 are closed is of sufficient duration to permit the switch 32 to close and the switch 48 to open. Similarly, the switch 32 is closed for a sufficient time interval to permit the resistance 126 to cool off and close the switch 132 before the switch 32 is opened. In other words, the switch 32 must be closed for a time interval sufficient to permit the heating element for the switch 132 to cool off and the switch 132 must be closed for a time interval sufficient to permit the heating element for the switch 32 to cool off. The electrical interlock illustrated in Fig. 3 prevents the closing of the circuit through one set of lights while the circuit through the other set is closed.

With the foregoing circuit, the minimum time possible is the time required for the thermostatic switches to cool off and reset. The maximum time may be varied over quite a wide range by adjustment of the resistances 40 and 140.

The traffic signal may also be formed to include a beacon light 80 controlled by a manually operated switch 82 and independently of the circuits for the red, green, and amber lights.

In those instances where amber lights are not used, the conductor 42 may be connected to the RE and RW lights and the conductor 72 may be connected to the RS and RN lights thereby providing for turning on the red lights on the same side on which the green lights are on before the lights "change."

In the modification illustrated in Fig. 4, use is

also made of thermostatically controlled switches, similar to those heretofore illustrated, for actuating the various sets of lights. In this modification, the RS, RN, GE, and GW lamps are all connected to an electrical conductor 210, and the RE, RW, GS, and GN lamps are connected to a conductor 212. The AE and AW lamps, being the amber east and west lamps, are connected to a conductor 214 while the AS and AN 5 10 15 20 25 30 35 40 45 50 55 60 65 70 75 70 amber lights are connected to a conductor 216. All of the foregoing lamps are grounded, and are connected through the foregoing conductors and control mechanism therefor to a source of current such as a battery 218, one side of which is also grounded. The other side of the battery is connected through a manually operated switch 220 to an electrical conductor 222 which is connected to the control mechanism. A manually controlled switch 223 may also be provided to control a circuit through a beacon light 225. The lamps, control mechanism, circuits, and battery 218 are all adapted to be mounted in a single housing and comprise a self-contained electric traffic signal which may be of a portable nature adapted for temporary installation at a traffic intersection.

In the position in which the control mechanism is illustrated in Fig. 4, the circuit through the lamps connected to the conductor 212 is closed so that the RE, RW, GS, and GN lamps are actuated. The conductor 222 is connected to one end 224 of a heater coil or resistance 226, the other end 228 of which is connected to the movable element 230 of normally closed switch 232, thereby establishing a circuit from the battery through the east and west red lamps and north and south green lamps. The switch 232 also closes the circuit through coil of relay 236, the movable element 238 of which carries the movable contacts of switch 244 which, as illustrated, is closed.

One of the stationary contacts of switch 244 has connected to it the conductor 216, while the other stationary contact is connected by a conductor 246 to the stationary contact of switch 248 which is normally open. The movable element 250 of switch 248 is also connected to the end 228 of the resistance element 226. After switches 220 and 232 are closed a predetermined time interval, for example 25 seconds, the heater element 226 will cause movable element 250 to move and close switch 248, thereby establishing a circuit through the conductor 246, switch 244, and the AS and AN amber lights. After the switch 248 has been closed for a predetermined time interval, for example 5 or 6 seconds, the heater element 226 will actuate the movable element 230 of switch 232 to open the same, thereby breaking the circuit through the RE, RW, GS, and GN lights and through the relay 236, thereby also opening the switch 244 and breaking the circuit through the AS and AN amber lights. A variable resistance 240, similar to the resistance 40, may be provided for varying the flow of current through the resistance 226, thereby to vary the time interval that the switches 232 and 248 are closed.

Simultaneously with the opening of switches 232 and 244 and the breaking of the circuits through the RE, RW, GS, GN, AS, and AN lamps, the movable element 238 of the relay 236 which carries the movable contacts of the switch 334 will move such contacts and close the switch 334, thereby closing the circuit through resistance 326 and the RS, RN, GE, and GW lamps. The

resistance 326 is similar to the resistance 226 and also has a variable resistance 340 arranged in parallel therewith as illustrated. After the switch 338 has been closed for a suitable time interval, for example 25 seconds, the heater element or resistance 326 will actuate movable element 353 of switch 348 and establish a circuit through the AE, AW amber lights while the circuit through the GE, GW, RS, and RN lights is still closed. The thermostatic switch 348 preferably is of the same type as the switch 248.

As soon as the resistance 226 cools off and the switch 233 closes, the circuit through the relay 238 will be closed thereby opening switch 334 and closing switch 244, thereby opening the circuit through the GE, GW, RS, RN, AE, and AW lamps and closing the circuit through the GS, GN, RE, and RW lamps. When the switch 232 resets, the switch 248 will open and, in accordance with the previous description, will close after the switch 232 has been closed a predetermined time interval. The system as illustrated in this modification should be designed so that the cooling off and resetting period of the switches 332 and 248 will permit the switches 334 and 348 to be closed on whatever time interval is desired.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. A traffic control adapted to be arranged at a traffic intersection comprising a circuit including a source of electric energy, a normally closed thermostatically controlled switch, a relay controlled switch and a set of signal lights comprising a "stop" signal light facing in one direction and a "go" signal light facing in a cross direction, a second circuit including said source of electric energy, a normally closed thermostatically controlled switch, a relay controlled switch and a second set of signal lights comprising a "stop" signal light facing in said cross direction and a "go" signal light facing in said one direction, and a relay operatively connected in one of said circuits for operating said relay controlled switches which are arranged so that one circuit is opened while the other circuit is closed.

2. A traffic control adapted to be arranged at a traffic intersection comprising a circuit including a source of electric energy, a normally closed thermostatically controlled switch, a relay controlled switch and a set of signal lights comprising a "stop" signal light facing in one direction and a "go" signal light facing in a cross direction, a second circuit including said source of electric energy, a normally closed thermostatically controlled switch, a relay controlled switch and a second set of signal lights comprising a "stop" signal light facing in said cross direction and a "go" signal light facing in said one direction, a relay operatively connected in one of said circuits for operating said relay controlled switches which are arranged so that one circuit is opened while the other circuit is closed, and means to prevent the opening of the relay controlled switch in one of said circuits while the thermostatically controlled switch therein is closed.

3. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electric energy, a circuit including a normally closed thermostatically operated switch for electrically connecting one of said sets of lights and said source, the other circuit including a normally closed thermostatically operated switch for electrically connecting the other of said sets of lights and said source, a relay in one of said circuits and a switch in each circuit controlled by said relay and arranged so that one of said relay controlled switches is opened while the other is closed.

4. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electric energy, a circuit including a normally closed thermostatically operated switch for electrically connecting one of said sets of lights and said source, the other circuit including a normally closed thermostatically operated switch for electrically connecting the other of said sets of lights and said source, a relay in one of said circuits and a switch in each circuit controlled by said relay and arranged so that one of said relay controlled switches is opened while the other is closed, and a relay in the other of said circuits cooperable with said other relay for preventing the closing of the relay controlled switch in one of said circuits when the thermostatically operated switch in the other of said circuits is closed.

5. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electric energy, a circuit including a normally closed thermostatically operated switch for electrically connecting one of said sets of lights and said source, the other circuit including a normally closed thermostatically operated switch for electrically connecting the other of said sets of lights and said source, a relay in one of said circuits, a switch in each circuit controlled by said relay and arranged so that one of said relay controlled switches is opened while the other is closed, and means to prevent the closing of the relay controlled switch in one of said circuits when the thermostatically controlled switch in the other of said circuits is closed.

6. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electric energy, a circuit

including a normally closed thermostatically operated switch for electrically connecting one of said sets of lights and said source, another circuit including a normally closed thermostatically operated switch for electrically connecting the other of said sets of lights and said source, each of said switches being adapted to open after a predetermined time interval, and means controlled by one of said circuits for alternately opening one of said circuits and closing the other of said circuits.

7. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electric energy, a circuit including a normally closed thermostatically operated switch for electrically connecting one of said sets of lights and said source, another circuit including a normally closed thermostatically operated switch for electrically connecting the other of said sets of lights and said source, each of said switches being adapted to open after a predetermined time interval, means controlled by one of said circuits for alternately opening one of said circuits and closing the other of said circuits, and an interlock between said circuits to prevent said means from opening one of said circuits while the thermostatically controlled switch in said last-mentioned circuit is closed.

8. A traffic control adapted to be arranged at a traffic intersection comprising a set of signal lights, said set comprising a "stop" signal light facing in one direction and a "go" signal light facing in a cross direction, a source of electric energy, a circuit operatively connecting said lights and source and including a switch, means responsive to the heat from a resistance in said circuit for opening said switch after a time interval, a second set of signal lights comprising a "stop" signal light facing in said cross direction and a "go" signal light facing in said one direction, a second circuit operatively connecting said second lights and source and including a second switch and means for closing said second switch simultaneously with the opening of said first-mentioned switch and for preventing the opening of said second switch until the signal lights in said second circuit have been deenergized.

9. A traffic control comprising a first circuit including a source of electric energy, a normally closed thermostatically controlled switch, and a set of signal lights, said set of lights comprising a "stop" signal light facing in one direction and a "go" signal light facing in a cross direction, a second circuit including said source of electric energy, a relay controlled switch and a second set of signal lights comprising a "stop" signal light facing in said cross direction and a "go" signal light facing in said one direction, and a relay operatively connected in said first circuit for operating said relay controlled switch which is arranged so that its circuit is opened while the first circuit is closed, said thermostatically controlled switch controlling the circuit through said relay and a relay operatively connected in said second circuit for closing said relay controlled switch when said first circuit opens and for preventing the opening of said relay controlled

switch until the signal lights in said second circuit have been deenergized.

10. A traffic control comprising a first circuit including a source of electric energy, a normally closed thermostatically controlled switch, and a set of signal lights, said set of lights comprising a "stop" signal light facing in one direction and a "go" signal light facing in a cross direction, a second circuit including said source of electric energy, a relay controlled switch and a second set of signal lights comprising a "stop" signal light facing in said cross direction and a "go" signal light facing in said one direction, and a relay operatively connected in said first circuit for operating said relay controlled switch which is arranged so that its circuit is opened while the first circuit is closed, said thermostatically controlled switch controlling the circuit through said relay, a third circuit including said source, a normally opened thermostatically controlled switch, a relay controlled switch and a "change" signal light, said normally opened thermostatically controlled switch being set to close before said normally closed thermostatically controlled switch in said first circuit opens, and said relay controlled switch being opened by said relay when said normally closed thermostatically controlled switch opens, and a fourth circuit including a normally opened thermostatically controlled switch, said relay controlled switch of said second circuit and a "change" signal light, said last-mentioned normally opened thermostatically controlled switch being set to close a predetermined time interval after said relay controlled switch is closed.

11. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electrical energy, a first circuit adapted for electrically connecting said source and one of said sets of signal lights and comprising a normally closed thermostatically controlled switch and a relay controlled switch, a second circuit including said relay and controlled by said thermostatically controlled switch and adapted for electrically connecting said relay to said source, a third circuit comprising a normally open thermostatically controlled switch, a switch controlled by said relay and adapted to be opened and closed simultaneously with the relay controlled switch in said first circuit, a "change" traffic signal and said source, a fourth circuit adapted for electrically connecting said source and said other of said sets of signal lights comprising a normally closed thermostatically controlled switch and a relay controlled switch, a fifth circuit including said source, said thermostatically controlled switch of said fourth circuit and a relay, and a sixth circuit including said source, a normally open thermostatically controlled switch, a relay controlled switch and a "change" traffic signal, said relay controlled switches in said fourth and sixth circuits being controlled by said first-mentioned relay and being adapted to be closed when the relay controlled switches in the first and third circuits are open and to be open when the relay controlled switches in the first and third circuits are closed, said second-mentioned relay being adapted to prevent the opening of the relay controlled

switches in the fourth and sixth circuits when the normally closed thermostatically controlled switch in the fourth circuit is closed, said normally open thermostatically controlled switch in the third circuit being set to close when the thermostatically controlled switch in the first circuit is closed and at the end of its closed period and said normally opened thermostatically controlled switch in said sixth circuit being set to close when the thermostatically controlled switch in the fourth circuit is closed and at the end of its closed period.

12. A traffic control adapted to be arranged at a traffic intersection comprising at least two sets of electric signal lights, one of said sets comprising a "stop" signal light facing in one direction and a "go" signal light facing in a cross direction and the other of said sets comprising a "stop" signal light facing in said cross direction and a "go" signal light facing in said one direction, a source of electrical energy, a first circuit adapted for electrically connecting said source and one of said sets of signal lights and comprising a normally closed thermostatically controlled switch and a relay controlled switch, a second circuit including said relay and controlled by said thermostatically controlled switch and adapted for electrically connecting said relay to said source, a third circuit comprising a normally open thermostatically controlled switch, a switch controlled by said relay and adapted to be opened and closed simultaneously with the relay controlled switch in said first circuit, a "change" traffic signal and said source, a fourth circuit

adapted for electrically connecting said source and said other of said sets of signal lights comprising a normally closed thermostatically controlled switch and a relay controlled switch, a fifth circuit including said source, said thermostatically controlled switch of said fourth circuit and a relay, and a sixth circuit including said source, a normally open thermostatically controlled switch, a relay controlled switch and a "change" traffic signal, said relay controlled switches in said fourth and sixth circuits being controlled by said first-mentioned relay and being adapted to be closed when the relay controlled switches in the first and third circuits are open and to be open when the relay controlled switches in the first and third circuits are closed, said second-mentioned relay being adapted to prevent the opening of the relay controlled switches in the fourth and sixth circuits when the normally closed thermostatically controlled switch in the fourth circuit is closed, said normally open thermostatically controlled switch in the third circuit being set to close when the thermostatically controlled switch in the first circuit is closed and at the end of its closed period and said normally opened thermostatically controlled switch in said sixth circuit being set to close when the thermostatically controlled switch in the fourth circuit is closed and at the end of its closed period, and means for varying the timing of at least one of said normally opened and one of said normally closed thermostatically controlled switches.

EARL F. HUBACKER.
